DESIGN FOR A SECRETARY

Frances M. McClure, New York, N. Y., assignor
to The Statton Furniture Manufacturing Com-
pany, Hagerstown, Md., a corporation of
Maryland

Application January 24, 1933. Serial No. 46,949

Term of patent 3½ years

To all whom it may concern:

Be it known that I, FRANCES M. MCCLURE, a citizen of the United States, residing at New York, in the county of New York and State of New York, have invented a new, original, and ornamental Design for a Secretary, of which the following is a specification, reference being had to the accompanying drawing, forming part thereof.

The figure is a perspective view of a secretary, showing my new design.

I claim:

The ornamental design for a secretary, as shown.

FRANCES M. MCCLURE.
